SQUEEZE DISPENSER FOR CLEANING FLUID OR THE LIKE

Lucian Kapuscinski, Atlanta, Ga., assignor to
Intex Products, Inc., Greenville, S.C.

Filed Mar. 26, 1973, Ser. No. 344,604

Term of patent 14 years

Int. Cl. D9—01

U.S. Cl. D9—2

Fig. 2.

Fig. 1.

Fig. 3.

FIG. 1 is an elevational view of a squeeze dispenser for cleaning fluid or the like embodying my new design;

FIG. 2 is a top plan view; and

FIG. 3 is a perspective view looking toward the bottom of FIG. 1.

I claim:

The ornamental design for a squeeze dispenser for cleaning fluid or the like, substantially as shown.
